UNITED STATES PATENT OFFICE.

VINCENZO MASSACESE, OF NEW YORK, N. Y.

SECTIONAL BED.

Application filed May 12, 1925. Serial No. 29,788.

This invention relates to sectional beds.

More particularly the present invention relates to the class of beds capable of being converted from the day bed or couch type to a double bed type. Beds of this class comprise a stationary section, and a section movable with respect to the stationary section, the latter having a bedding frame or spring mattress which is movable from a non-supporting position to a supporting position when said movable section is extended in the obtainment of the double bed type.

Some of the objects of the present invention are: to incorporate in a bed comprising a stationary section and a movable section mechanical means or mechanism for raising and lowering the bedding frame or spring mattress, which is thoroughly efficient and effectual for raising and lowering said bedding frame or spring mattress, and which also serves for supporting said bedding frame or spring mattress in its raised position; to provide anti-friction devices for facilitating the movement of the movable bed section, and to facilitate the raising and lowering of the bedding frame or spring mattress; and to provide connections between the stationary bed section and the movable bed section to lend rigidity to the bed with the movable section thereof in either position.

With the foregoing and other objects in view, the invention resides in the particular provision, relative disposition and operation of the parts hereinafter fully described and illustrated in the accompanying drawings, in which—

Figure 1 is an end elevation of a bed embodying the present invention, and showing the movable section extended.

Fig. 2 is a view similar to Fig. 1 but showing the bedding frame of the stationary section lowered to permit the movable section to be moved over the stationary section.

Fig. 3 is a plan view of the bed with the sections extended and central portions being broken away.

Fig. 4 is a transverse sectional view taken on the line 4—4 of Fig. 3 and looking in the direction of the arrows.

Fig. 5 is a detail vertical sectional view taken on the line 5—5 of Fig. 2.

Fig. 6 is a transverse sectional view show-

ing the movable section of the bed in position beneath the stationary section.

Generally stated, the bed of the present invention comprises a movable section 10, a stationary section 11 and supporting and shifting means 12 which serves and operates for a purpose to be hereinafter explained.

The movable section 10 in the present instance includes a frame structure 13 comprising ends 14 having legs 15, side rails 16 which connects the ends 14, and a bedding support or spring mattress 17 which is supported by the transverse rails 18 of the ends 14. The legs 15 at one side of the section are each provided with a caster or roller 19, whereas, the legs 15 on the opposite side of the section 10 are shorter and are each provided with a roller 20.

The stationary section 11, in the present instance, includes a frame structure 21 consisting of uprights in the nature of angle irons 22 which are connected together by longitudinals in the nature of angle irons 23 and 24 and transverse rails in the nature of angle irons 25 and 26 at each end of the structure 21; there being a bedding support or spring mattress 27 arranged for movement in the structure 21. The bedding structure 27 consists of end rails or angle irons 28 each of which has mounted at the opposite ends thereof a roller 29 which is in rolling contact with a portion of the upright 22 associated therewith. In order to maintain the movable association of the section 10 with respect to the section 11 there is provided a pair of connections 30 and 31 pivotally connected together as at 32 and respectively connected to certain of the legs 15 of the section 10 as at 33 and to the rails 26 of the section 11 as at 34. The connections 33 and 34 are pivotal connections. It is also to be noted that the rollers 20 are in rolling contact with portions respectively of the transverse rails 25. It should now be understood that the movable section 10 may be moved from a position over the stationary section 11 as shown in Fig. 6 to a position beside the section 11 as shown in Fig. 1 for instance.

The supporting and shifting means 12 serves to support the bedding support 27 and also serves for effecting the raising and lowering of the same. The said means 12 in the present instance consists of and operates as presently described. Pivots 105 110

nected to the longitudinal 23 of the movable section 11 by the employment of bearings 35 attached to said longitudinal, is an actuator and support 36. The said actuator and support 36 is of U-shape to provide a central portion received in the bearings 35 and end members 37 which are disposed respectively adjacent the end rails 28. Each of the members 37 has a hand grip 38. Each of the 10 depending flanges of each of the end rails 28 is provided with an elongated slot 39 which respectively receive pins 40 carried by the members 37, there being a suitable nut 41 on the end of each pin 40. Toggles in the form of jointed supports or braces 42 are employed for aiding in holding the bedding support 27 in its raised position. Each toggle 42 consists of a plate 43 to which are pivotally connected members 44 15 in turn pivotally connected to the transverse rails 28 and 26. Pivotally connected to each plate 43 is a push and pull rod 45, which rods 45 are pivotally connected respectively to the members 37, there being a spring 46 20 connected to the free end of each rod 45 as at 47, and the opposite end of each spring is connected as at 48 to one of the uprights 22. A rest 49 is connected to each of the rails 28, which, with the plates 43 serve to 25 support the bedding support 27 when it is moved to its non-supporting position as shown in Fig. 4. When it is desired to move the bedding support 27 to a supporting position, either of the hand grips 38 is 30 taken hold of and an upward pull is exerted on the member 37 which will impart upward movement to the end rails 28 by virtue of the pins 45. The end members 37 move with and with respect to the end rails 28 35 and at the same time the toggles 42 are brought into play as shown in Fig. 1; the members 44 being out of alignment due to the proportions and arrangement of the plate 43 and members 44 of each toggle. 40 The springs 46 releasably maintaining the out of alignment condition of the toggle parts and assist in raising the bedding support 27. When the toggles 42 are in the condition shown in Fig. 1 the end members 45 37 are in a vertical position and both the toggles and the end members 37 serve to support the bedding support 27 in a supporting position. Any pressure or weight on the bedding support 27 will tend to keep 40 the members 37 vertical and prevent the accidental lowering of said bedding support 27. When it is desired to lower the bedding support 27 the out of alignment condition of the toggles 42 is upset, whereupon 45 the actuator 36 may be moved pivotally to cause the lowering of the bedding support 27. It is to be understood that the raising and lowering of the bedding support 27 will 50 be performed after the movable section 10 55 has been moved to an extended position, the

pairs of connections 30 and 31 coacting in the movement of the section 11.

I claim:

1. In a sectional bed, a stationary section comprising a frame structure and a movable bedding support; means for effecting the raising and lowering of said bedding support and for holding it raised and lowered, said means comprising a U-shaped element connected to a part of the frame structure for pivotal movement, said bedding support having end rails, each of said end rails having a longitudinal slot therein, each of the side legs of the U-shaped element having a pin which is disposed in the slot of one of the end rails to which it is related, jointed props connected to and arranged between said end rails respectively and the frame structure, a rod pivotally connected to and arranged between each jointed prop and one side leg of the U-shaped element to which it is related, and a coil spring connected between each of said rods and the frame structure.

2. In a sectional bed, a stationary section comprising a frame structure including uprights and a bedding support having rollers respectively in rolling contact with portions of said uprights to guide said bedding support for up and down movement; jointed supports each pivotally connected to said frame structure and to said bedding support, and an actuator-support movably carried by said frame structure and operatively connected to said bedding support and 95 jointed supports to effect the raising and lowering of said bedding support, said jointed supports and actuator-support serving to hold said bedding support in a raised position.

3. In a sectional bed, a stationary section comprising a frame structure including uprights and a bedding support having rollers respectively in rolling contact with portions of said uprights to guide said bedding support for up and down movement; jointed supports each pivotally connected to said frame structure and to said bedding support, and an actuator-support movably carried by said frame structure and operatively 110 connected to said bedding support and jointed supports to effect the raising and lowering of said bedding support, said jointed supports and actuator-support serving to hold said bedding support in a raised 115 position, and means acting on said jointed supports to prevent their collapse when the bedding support is up in supporting position, said means assisting in the raising of the bedding support, and said means being yieldable to permit the collapse of said jointed supports to permit the bedding support to be lowered in response to the actuation of said actuator-support.

VINCENZO MASSACESE.
